(57) **CLAIM**

I claim the ornamental design for a grill tong with angled handle, as shown and described.

DESCRIPTION

FIG. 1 is a top, front and side elevation perspective view of the grill tong with angled handle;

FIG. 2 is a side elevation view of the grill tong with angled handle, wherein the opposite side is a mirror image of same;

FIG. 3 is a top plan view of the grill tong with angled handle;

FIG. 4 is a top plan perspective view of the grill tong with angled handle;

FIG. 5 is bottom plan perspective view of the grill tong with angled handle; and,

FIG. 6 is a bottom plan view of the grill tong with angled handle.
